RING CLOSING PLIERS

Lawrence H. Heuer, Detroit, Mich.

Application February 24, 1947, Serial No. 730,493

1 Claim.

(Cl. 81—15)

1

This invention relates to an improved hog ring or clip and to improved mechanism for closing the same.

Rings of this general type are widely used in the automobile body industry in securing the springs of a spring cushion assembly together or in securing the same to surrounding boundary wires and also in securing upholstery material to a spring cushion assembly.

Such rings commonly comprise an angular split ring blank exhibiting a pair of spaced apart arms adapted to be gripped between a pair of jaws of a tool to have the two arms of the ring moved toward each other and into crossed overlapping relationship. The two ends of the arms are normally so closed that the ring assumes an angular shape.

When such rings are employed to secure two spring coils of a cushion spring assembly together it is not uncommon for the crossed arms of the ring to open to be spread apart during use of the spring cushion by the pressure exerted by the separate spring coils on the ends of the ring. It is not unusual in spring cushion practice to find several of these hog rings, as they are termed in the trade, with their ends pulled sufficiently apart so as to release the elements that were intended to be held together thereby.

An object of this invention is to provide a hog ring which is so shaped and which is closed in such a manner that when closed it assumes a substantially circular shape with the two ends of the ring overlapping each other and extending alongside each other in substantially concentric relationship.

Preferably the ends overlap each other throughout a substantial arc of the circumference of the ring. Such a ring will resist a very substantial amount of opening pressure exerted inwardly thereof because the pressure is exerted against the inner circumference of a ring made up of overlapped coils instead of against a pair of crossed arms whereby due to angular leverage the arms may be readily spread apart. It has been discovered that a ring constructed in the manner herein set forth possesses substantially twice the resistance to spreading or separation of its ends as is possessed by the old crossed arm type of ring.

This particular ring blank is so shaped and is so supported within my improved closing mechanism that as the opposed arcuate complementary ends are moved toward each other, they are brought into overlapping alignment. In other words, as one end overlaps the other, the two overlapping

ends are brought into adjacent side-by-side concentric relationship and the closed ring now presents a circular shape.

The original ring blank has a base which is preferably convexed inwardly between the two arcuate complementary ends. The base is of substantial length so as to provide sufficient ring stock to permit a substantial overlap of the end portions of the ring when the ring is closed.

10 Improved closing mechanism is provided for the improved ring. Such improved closing mechanism comprises a pair of jaws supported to be moved toward and away from each other. Specifically, the two jaws may be pivotally coupled together for swingable movement toward and away from each other. The opposed faces of these complementary jaws are provided with arcuate ring supporting grooves adapted to support a ring and to advance its ends into overlapping concentric relationship as above described.

15 A meritorious feature is that these grooves constitute as to each jaw arcs of successive convolutions of a helix. The grooves of the two jaws are inclined in opposite directions away from the 20 axis of a ring supported therebetween whereby the two ends of the ring are moved into closely adjacent overlapping concentric relationship as the ring is closed.

The jaw members are so constructed as to provide overlapping ring supporting portions disposed between the jaw faces which portions are adapted to engage the base of the ring and hold it inwardly of the ring so as to prevent angular outward deformation of the base and in such a manner that the ring closes into circular shape 35 rather than into an angular shape.

Other objects, advantages and meritorious features will more fully appear in the following description, claim and drawings wherein:

40 Fig. 1 is a side elevation of the improved ring closing tool of this invention showing a ring therein.

Fig. 2 is a sectional view taken on the line 2—2 of Fig. 1, but with the ring removed.

45 Fig. 3 is a sectional view taken on the line 3—3 of Fig. 1, but with the ring removed.

Fig. 4 is a side elevation of a ring blank embodying the improved ring of this invention.

Fig. 5 is a plan of the ring blank shown in Fig. 4.

50 Fig. 6 is a side elevation of the jaws of the tool shown in association with the ring moved partially toward the closed position.

Fig. 7 is a plan of the ring shown in Fig. 6.

Fig. 8 is a fragmentary elevation similar to Fig. 55 6 but showing the ring completely closed.

Fig. 9 is a plan view of the ring completely closed as shown in Fig. 8.

Fig. 10 is a fragmentary elevation of the jaws of the tool similar to the view of Fig. 6, but showing the ring more completely closed than it is in Fig. 6.

Fig. 11 is a plan view of the ring shown in Fig. 10.

Fig. 12 is a fragmentary view showing completely closed rings securing separate spring elements of a spring assembly together.

My improved ring blank illustrated in Figs. 4 and 5 comprises a base portion 20 and opposed arcuate complementary end portions 22. The base portion might be described as approximately flat though it is preferably slightly convex inwardly between the end portions as indicated particularly at 24. The base portion has such a length as to permit the end portions to be rolled inwardly into overlapping relationship to overlap each other for a substantial distance as shown in Figs. 10 through 12.

In Fig. 1 there is shown a closing mechanism or tool adapted to be used to close a ring. The tool shown is of the general character of the conventional hand tool but the jaws are shaped as herein set forth to close the ring into circular form. The tool illustrated comprises a pair of handle elements 26 and 28 pivoted together at 30. Each handle element is provided with a jaw portion 32. The opposed jaws are provided with arcuate grooves adapted to receive the arcuate ends of the ring blank as shown in Figs. 1, 6, 8 and 10. Preferably each jaw face is provided with a plurality of grooves which lie closely adjacent to each other and constitute arcs of successive convolutions of a helix. These grooves are indicated as 34 and illustrated particularly in Figs. 2 and 3.

As the ring is supported between complementary grooves of the opposed jaws the ends are brought together as shown in Figs. 6 and 7. These ends of the ring are picked up and guided by adjacent grooves of the complementary jaws as shown in Figs. 8 and 10 so as to be moved into overlapping relationship throughout a substantial arc of the circumference of the ring.

The grooves of one jaw are inclined oppositely with respect to the grooves of the other jaw as measured against the axis of a ring supported therebetween or as against the axis of the helix of which the grooves constitute arcs of successive convolutions as shown in Figs. 2 and 3.

It will be seen that if the ring ends were merely moved to the position shown in Figs. 10 and 11, that they would be brought into substantially concentric overlapping relationship throughout a considerable portion of their circumference and the ring would have assumed a substantially circular shape, however, if the ring ends are moved further to the position shown in Figs. 8 and 9, then a much more complete closure is effected and a substantially greater overlap is accomplished and the ring will present greater resistance of separation of its end portions.

What I claim is:

20 Ring closing mechanism comprising a pair of cooperating jaws pivotally supported for swingable movement toward and away from each other, said jaws having opposed faces provided with cooperating arcuate ring supporting grooves constituting arcs of successive convolutions of a helix on each jaw face, and upon closure of said jaws said grooves forming one continuous helical groove, said jaws including overlapping ring supporting portions disposed between the jaw faces 30 and being convex inwardly between said faces.
